UNITED STATES PATENT OFFICE

THURE W. ALM, OF STEWART MANOR, NEW YORK, ASSIGNOR TO INTERNATIONAL CIGAR
MACHINERY COMPANY, A CORPORATION OF NEW JERSEY

AUTOMATIC WRAPPER FEED CONTROL FOR ARTICLE-ENVELOPING MACHINES

Application filed January 29, 1931. Serial No. 512,185.

This invention relates to wrapper or envelop feeds for article enveloping machines in which the wrapping material, such as cellophane, tinfoil, etc., is fed in a continuous web from a reel, and the articles to be wrapped, such as cigars, etc., are intermittently conveyed into position for delivery to the wrapping mechanism, on an endless conveyor.

The main object of this invention is to automatically control the wrapper feed in such a way that when one of the articles on the article conveyor is missing, the wrapper feed will stop during the corresponding enveloping cycle and so eliminate waste of wrapping material.

This object is achieved by means of a locking device actuated by a feeler which engages with each article as it arrives in position for delivery to the wrapping mechanism, so that in case of a missing article, this feeler is no longer held in its normal position but moves into the unoccupied space, thereby tripping a lock lever which acts as a clutch between the driving mechanism of the machine and the wrapper feed mechanism. The wrapper feed mechanism operates with a step by step motion in such a manner that the next step brings the said lock lever back into its drive engaging position, ready to operate the wrapper feed if the conveyor brings an article to be wrapped, otherwise the feeler will again trip the lock lever and the wrapper feed mechanism will stop until an article arrives in position for delivery to the wrapping mechanism. With this and other objects not specifically mentioned in view, the invention consists in certain constructions and combinations which will be hereinafter fully described and then specifically set forth in the claims hereunto appended.

In the accompanying drawing, which shows the invention applied to a cigar enveloping machine:

Fig. 1 is a side elevation of the improved wrapper feed control mechanism;

Fig. 2 is an end elevation of the same;

Fig. 3 is a side elevation showing the manner in which the feeler trips the lock lever when there is no article at the wrapping station; and

Fig. 4 is a top view of the locking mechanism taken on line 4—4 of Fig. 1.

In carrying the invention into effect there is provided means for forwarding articles to be enveloped and means controlled by the forwarding movement of the articles for feeding a web of wrapping material for said articles. In the best constructions contemplated, the forwarding means includes a conveyor table, sprockets intermittently moving chains on said sprockets for conveying the articles along said table, and ratchet mechanism for intermittently rotating said sprockets and the web feeding means includes a feeler adapted to engage the leading article on the conveyor chains and connected to a knock-out screw adapted to trip a latch lever which normally locks a reciprocating rod to a rack engaging a gear on one of the web-feeding rollers. These various means and parts may be widely varied in construction within the scope of the claims for the particular machine selected to illustrate the invention is but one of many possible concrete embodiments of the same. The invention, therefore, is not to be restricted to the specific construction shown and described.

The cigars C to be wrapped are placed on the conveyor table 10 and moved towards the end A of the conveyor table by means of a pair of endless chains 11 equipped with pushers 12. The chains 11 are intermittently driven from sprockets 13 on shaft 14 supported by main frame 15. On shaft 14 is mounted a ratchet 16, the pawl 17 of which is pivoted in the upper arm of a double lever 18 loosely mounted on shaft 14, the lower arm of lever 18 carrying a stud 19 engaging in a slot of a push rod 20 operated from a bell-crank lever 21 having a cam roller running in a cam track in the rear face of cam 22 on shaft 23, as shown in Fig. 1. The motion of lever 21, through rod 20 and lever 18, produces reciprocating motion of pawl 17, thereby, through ratchet 16, shaft 14, and sprocket 13, imparting an intermittent forward motion to the chains 11 carrying the cigars C into position to be delivered to a wrapping mechanism, not shown.

Pivot stud 19 of lever 18 carries a connect-

ing rod 24 pivoted to a lever 25 mounted on shaft 26 supported from the main frame 15 of the machine. On shaft 26 is mounted a lever 27 connected by means of a connecting 5 rod 28 to a lever 29 loosely mounted on shaft 14. The connecting rod 28 is provided with an integral feeler 30 which thus partakes of the reciprocating motion produced by the motion of lever 21. To a projection of connecting rod 24 is fastened a finger 31 carrying an adjustable knock-out screw 32.

The wrapper feed mechanism is driven by means of a cam 33 on shaft 23 actuating, through bell crank lever 34, the vertical rod 15 35 on which is mounted a supporting lug 36 which on its upward stroke takes along a bearing lug 37 slidably mounted on rod 35. The lever 34 has a cam roller engaging a cam track in the rear face of cam 33 which is disposed in front of and spaced from the cam 22 on the shaft 23, as shown in Fig. 1. To bearing lug 37 is attached a rack 38 actuating a gear 39, which through a one-directional means such as a ball clutch 40 of usual construction, drives the wrapper feed shaft 41 carrying the reel R, the ball clutch 40 being so arranged that the shaft 41 is driven only on the downward motion of rack 38, remaining at rest on the upward stroke.

30 To supporting lug 36 is pivoted a spring-tensioned latch lever 42 locking the bearing lug 37 and the rack 38 to the supporting lug 36 and vertical rod 35. The latch lever 42 is normally in its locking position so that the rack 38 will partake of the motion of rod 35 and thus will operate the wrapper feed.

When a cigar is missing on the article conveyor as it arrives at wrapping station A, the feeler 30 will not be stopped in its normal position but will be moved by a spring attached to the lever 27, as shown in Fig. 1, some distance into slots in the ends of the table 10 towards the next following cigar C as indicated by the arrow in Fig. 3, thereby bringing knock-out screw 32 into engagement with latch lever 42 and tripping the same, thus disengaging the bearing lug 37 from the supporting lug 36 so that the rod 35 will now move downward without taking along the rack 38 and thus cause the wrapper feed to stop. During this operation the stud 19 moves in the slot of the pusher rod 20 thus permitting the connecting rod to move forward to carry the knock-out screw into tripping position. As the lock lever 42 is provided with a tension spring 43, the former will, on the next upward stroke of rod 35, snap back into locking position with bearing lug 37, provided that there is a cigar arriving at wrapping station A which through feeler 30 will prevent the knock-out screw 32 from tripping the latch lever 42.

What is claimed is:

1. In a wrapper feed control for article-enveloping machines, the combination with

means for forwarding articles, of mechanism controlled by the forwarding movement of the articles for feeding a web of wrapping material for said articles.

2. In a wrapper feed control for article-enveloping machine, the combination with means for forwarding articles, of mechanism controlled by the forwarding movement of the articles for feeding a web of wrapping material for said articles, said means including a conveyor table adapted to support the articles, a shaft, sprockets on said shaft, chains running over said sprockets, pushers on said chains adapted to forward the articles along said table, and ratchet 75 mechanism for intermittently rotating said shaft whereby to intermittently forward the articles.

3. In a wrapper feed control for article-enveloping machines, the combination with means for forwarding articles, of mechanism controlled by the forwarding movement of the articles for feeding a web of wrapping material for said articles, said means including a shaft, a sprocket and a 85 ratchet fixed on said shaft, a chain running over said sprocket, a lever loosely mounted on said shaft, a pawl on one end of said lever engaging said ratchet, a push rod connected to the other end of said lever, a bell 90 crank lever connected to said lever, and a cam for intermittently actuating said bell crank lever, whereby to intermittently forward the articles.

4. In a wrapper feed control for article-enveloping machines, the combination with means for forwarding articles, of mechanism controlled by the forwarding movement of the articles for feeding a web of wrapping material for said articles, said 100 mechanism including a pair of cooperating feed rollers, a gear connected to one of said rollers, a reciprocating rod, a rack slidably mounted on said rod and arranged to engage said gear, a spring-tensioned latch lever carried by said rod and adapted to lock said rack to said rod, a knock-out screw arranged to trip said lever to release said rack, and a feeler connected to said screw and arranged to be engaged by the forwarded articles to 105 disengage said screw from said lever.

5. In a wrapper feed control for article-enveloping machines, the combination with means for forwarding articles, of mechanism controlled by the forwarding movement of the articles for feeding a web of wrapping material for said articles, said mechanism including a reciprocating rod, a pair of feed rollers adapted to feed the web of wrapping material, a gear connected to one of said rollers, a rack slidably mounted on said rod, a spring-tensioned latch lever carried by said rod and adapted to lock said rack to said rod, a bell crank lever connected to one end of said rod, and a cam for actuating said bell 110 120 125 130

crank lever whereby to reciprocate said rod to feed the material.

6. In a wrapper feed control for article-enveloping machines, the combination with
5 means for forwarding articles, of mechanism controlled by the forwarding movement of the articles for feeding a web of wrapping material for said articles, said mechanism including a knock-out screw, a connecting
10 rod carrying said screw, a connecting rod having a feeler in the path of the forwarded articles, a lever connecting said rods, and a spring urging the feeler toward the forwarded articles.

15 7. The combination with mechanism for forwarding a row of cigars one by one into predetermined position ready to be fed to an enveloping machine, of devices including a feeler engaging the foremost cigar in the
20 row for controlling the forward feed of the row, a feed for feeding a length of wrapping material for wrapping the cigar in position to be fed, and control means connected to said feeler and said feed to prevent feeding
25 of said length of material when there is no cigar in said predetermined position.

In testimony whereof, I have signed my name to this specification.
